UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,668, dated February 27, 1883.

Application filed January 25, 1883. Term of patent 3½ years.

To all whom it may concern:

Be it known that I, WINTHROP L. JACOBS, of East Orange, Essex county, New Jersey, have invented a new and original Design for 5 Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is broken up into a series of 15 irregular right-lined figures having separating outlines and being variously ornamented. Over this ground and irregularly traversing it is a system, *b*, of running stems and flowers,

as shown in the photograph, each large figure of the ground having its special group of flowers, portions of which, however, run out over adjacent figures of the ground. 20

I claim—

1. The design for a ground for a carpet, consisting of the ground *a*, substantially as shown 25 and described.
2. The design for a carpet, consisting of the running-flower system *b*, substantially as shown and described.
3. The design for a carpet, consisting of the 30 flower system *b* and the ground *a*, substantially as shown and described.

WINTHROP L. JACOBS.
